UNITED STATES PATENT OFFICE.

WILLIAM R. BUSENBARK, OF AKRON, OHIO.

SHIPPING-RECEPTACLE FOR AUTOMOBILE-TIRES.

1,196,842.

Specification of Letters Patent. Patented Sept. 5, 1916.

Application filed December 20, 1915. Serial No. 67,733.

To all whom it may concern:

Be it known that I, WILLIAM R. BUSENBARK, a citizen of the United States, residing at Akron, county of Summit, State of Ohio, have invented a certain new and useful Improvement in Shipping - Receptacles for Automobile-Tires, and declare the following to be a full, clear, and exact description of the same, such as will enable others skilled in the art to which it pertains to make and use the same, reference being had to the accompanying drawings, which form a part of this specification.

Often automobile tires are shipped in small lots containing less than a dozen tires, and the practice now is to place such tires in a stack, surround them with a protective sheathing or wall, and inclose the whole in a piece of burlap. This makes an expensive package because of the time required in forming it and for the further reason that the burlap used for a covering is an expensive material.

The object of the present invention is to make a simple and inexpensive container for small lots of tires, whereby the packages may be made up quickly and conveniently and at a low cost and will be adequately protected against damage during shipping.

The various features of novelty whereby my invention is characterized will hereinafter be pointed out with particularity in the claims; but, for a full understanding of my invention and of its object and advantages, reference may be had to the following detailed description taken in connection with the accompanying drawings, wherein:

Figure 1 is a view of one of my improved containers flattened out for shipping and storing purposes; Fig. 2 is a top plan view of a package of tires inclosed in the container; Fig. 3 is a section taken approximately on line 3—3 of Fig. 2, the tires being shown partly in elevation and partly in section; and Fig. 4 is an elevation of the retaining rod.

Referring to the drawing, 1 represents a strip of stiff cardboard or other suitable, cheap and yet comparatively strong, bendable material having a length sufficient to

permit the sheet to be bent into the form of a cylinder large enough to surround a tire of a given size and having a width or height equal to the height of a stack containing any desired number of tires. Projecting from the top and bottom of the sheet are flaps, 2, preferably formed integral with the body of the sheet. The flaps are of any desired length but are preferably longer than the radial thickness of the tires to be packaged, so that when the container is bent into the form of a cylinder around a stack of tires and the flaps are folded inwardly, the flaps form a complete protection for the ends of the stack. The flaps are preferably formed by using a sheet having a height equal to the height of the cylinder or container plus twice the height of one of the flaps, the sheet being then simply slit inwardly from its top and bottom edges, at intervals, for a distance equal to the length of the flaps desired. The sheet may also be provided with an extension or flap, 3, at one end which will permit a lap joint to be made in the cylinder.

At intervals along the sheet are placed tie members, 4, in the form of wires or bands, each of a length greater than the combined height of the member 1 and its flaps, and each arranged so that it overlies the body member and also one of the upper and one of the lower flaps. The tie members are secured in place, preferably by means of staples, 5, driven over the same through the underlying material. After a package has been made up by closing the container around a stack of tires, the ends of the tie members are joined together in any suitable way so as to hold the flaps securely in their inwardly folded positions. This may conveniently be accomplished by providing each end of each of the tie rods with an eye, 6, and so proportioning the parts that the eyes at each end of the package will register with each other at the axle of the stack of tires. All the free ends of the tie members at each end of the package may then be connected together by passing a holding device through the registering eyes. However, in order to make the container fit snugly upon the stack of tires and prevent the tires from

- rubbing one upon the other, I prefer to connect the ends of the tie members at one end of the package with those at the other end of the package in such a way that the two centers from which the tie members radiate are drawn toward each other, thus causing the flaps to be drawn snugly over the ends of the stack, giving the ends of the package a dish shaped appearance. This can 10 conveniently be accomplished by passing through the two groups of registering eyes a rod or other device, 7, having at its ends hooks, 8, the length of the rod being such that the tie members will be drawn taut.
- 15 The resiliency of the tires will permit the parts to yield enough to slip the hooks in place or, if desired, one end of the rod may be left straight and may be bent back into a hook shape after being passed through the 20 eyes.
- The lap joint may be produced by passing staples, 9, or other fastening means through the end flap 3 and the opposite end of the member 1, as indicated in Fig. 2. If desired, transverse tie members or hoops, 10, 25 may be provided, these members being similar to the members 4 and having their ends twisted together as indicated at 11 when the blank is bent into the form of a cylinder.
- 30 Furthermore, these transverse tie members or hoops may be used not only as reinforcing members but to hold the container in its cylindrical shape and cause it to fit snugly around the stack of tires.
- 35 While I have illustrated and described with particularity only a single preferred form of my invention, I do not desire to be limited to the exact structural details thus illustrated and described; but intend to 40 cover all forms and arrangements which come within the terms employed in the definitions of my invention constituting the appended claims.
- I claim:
- 45 1. A container for a stack of tires comprising a hollow cylinder large enough to receive the stack, flaps at one end of the cylinder adapted to be folded inwardly over one end of the stack, and holding devices at 50 tached to the flaps and adapted to be secured together to retain the flaps folded inwardly.
- 55 2. A container for a stack of tires comprising a hollow cylinder large enough to receive the stack, flaps at one end of the cylinder adapted to be folded inwardly over one end of the stack, holding elements secured to the flaps and projecting from the 60 ends of the latter toward the axis of the cylinder when the flaps are folded inwardly, and means for connecting the several holding devices together.
- 65 3. A container for a stack of tires comprising a hollow cylinder large enough to

receive the stack, flaps at one end of the 65 cylinder adapted to be folded inwardly over one end of the stack, a series of distributed tie members secured to the cylinder and extending lengthwise thereof and over correspondingly-located flaps, and means associated with the tie members for securing them in a position to retain the flaps folded inwardly. 70

4. A container for a stack of tires comprising a hollow cylinder large enough to 75 receive the stack, flaps at the ends of the cylinder adapted to be folded inwardly over the ends of the stack, and tie members distributed around the cylinder and extending throughout the length thereof and across 80 correspondingly-located flaps, and means for fastening the ends of said tie members together to hold the flaps folded inwardly.

5. A container for a stack of tires comprising a hollow cylinder large enough to 85 receive the stack, flaps at the ends of the cylinder adapted to be folded inwardly over the ends of the stack, a series of tie members distributed around the cylinder and extending lengthwise of the same, the tie members 90 being continued across correspondingly-located flaps and being attached both to the body of the cylinder and to the flaps over which they pass, and means for fastening the ends of said tie members together to 95 hold the flaps folded inwardly.

6. A package comprising a stack of tires, a container of sheet material bent into a cylinder around the stack and having at its ends flaps overlying and underlying the said 100 stack, tie members extending from the top to the bottom and radially across the ends of the package, and means extending between the groups of tie member portions at each end of the stack and holding them 105 apart at a distance less than the height of the stack so as to give the ends of the package a dished appearance.

7. A container comprising a cylinder formed out of a sheet of comparatively stiff 110 bendable material having its two ends fashioned into flaps, a series of distributed tie members secured to the cylinder and extending radially thereof over correspondingly located flaps, and means connecting the tie 115 members at one end of the cylinder with those at the other end.

8. A container comprising a cylinder made out of a sheet of comparatively stiff 120 bendable material having its ends fashioned into flaps, a series of distributed tie members secured to the cylinder and extending lengthwise thereof and over correspondingly located flaps, the free ends of said tie members being provided with eyes, and means 125 adapted to pass through said eyes for securing the free ends of the tie members.

9. A container comprising a cylinder

made out of a sheet of comparatively stiff bendable material having its ends fashioned into flaps, a series of distributed tie members secured to the cylinder and extending lengthwise thereof and over correspondingly located flaps, said tie members having eyes in their free ends, and a holding device adapted to lie at the axis of the cylinder and having hooks at its ends for engaging with the aforesaid eyes. 10
5

In testimony whereof, I sign this specification.

WILLIAM R. BUSENBARK.
